UNITED STATES PATENT OFFICE

JOHN N. KAUMANS AND ELISHA BRIDGES, OF MONTROSE, MISSOURI

DRILL JAR

Application filed July 11, 1931. Serial No. 550,242.

The present invention relates generally to well drilling apparatus and more particularly to new and useful improvements in drill jars and has for its primary object to provide, in a manner as hereinafter set forth, a device of this character embodying a novel construction, combination and arrangement of parts whereby loss of the bit will be prevented should the jar links or members be broken.

Other objects of the invention are to provide a drill jar of the character described which will be simple in construction, strong, durable, efficient and reliable in use and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:

Figure 1 is a view in side elevation of a drill jar in accordance with this invention showing the bit mounted thereon.

Figure 2 is a view showing the drill jar in vertical section.

Figure 3 is a view of the drill jar with the barrel or casing removed.

Figure 4 is a view partially in vertical section and partially in side elevation of the upper portion of the drill jar with the barrel or casing removed therefrom.

Figure 5 is a detail view in vertical section through the cable coupling socket.

Figure 6 is a view in horizontal cross section taken substantially on the line 6-6 of Figure 4 looking downwardly, as indicated by the arrows.

Figure 7 is a detail view in top plan of the cable coupling socket.

Referring now to the drawing in detail, it will be seen that the reference numeral 1 designates a drill rod having threadedly mounted on its lower end the bit 2, said bit being threadedly coupled to the rod 1, as at 3.

Integral with the upper end of the drill rod 1 is a lower jar member 4 which includes a

threaded portion 5 and a vertically slotted upper portion 6.

The reference numeral 7 designates the upper jar member including a depending slotted portion or loop 8 which is slidably connected with the slotted portion 6 of the lower jar member 4.

The upper jar member 7 further includes a tapered polygonal portion 9 for engagement by a suitable tool such as a wrench, above which is disposed a cylindrical head 10. A threaded shank 17 extends upwardly from the head 10 of the upper jar member and threadedly mounted thereon is a tapered socket member 11 in which one end portion of the drill cable 12 is inserted and anchored in any suitable manner, as at 13.

The reference numeral 14 designates an elongated barrel or casing having its lower end portion internally threaded and screwed on the portion 5 of the lower jar member 4, as illustrated to advantage in Figure 2 of the drawings. The barrel or casing 14 encloses the jar members and the cable socket 11, as well as the lower end portion of the cable. At its upper end the barrel or casing 14 terminates in a reduced neck 15 which provides means for permitting a suitable "fishing" or grappling tool to gain a hold should the cable 12 break. In addition, the neck 15 prevents an excessive amount of dirt, rock and other matter from entering the barrel or casing through the upper end thereof and said neck still further prevents excessive lateral movement of the upper end of the barrel or casing relative to the cable.

In its lower portions the barrel or casing 14 is provided with a plurality of openings 16 to permit a suitable actuating tool to be operatively engaged therewith and also to permit the escape of foreign matter which may get into the barrel or casing.

Should either of the jar members break or should the socket member 11 be separated therefrom, the tool will not be detached from the cable for the reason that the socket member cannot pass upwardly through the barrel or casing 14 beyond the neck 15 and it will thus be seen that the tool may be withdrawn.

from the hole. Then, as before stated, should the cable 12 break, a suitable grappling tool may be lowered into the well and engaged with the reduced neck 15. The threaded shank by which the socket member 11 is connected to the upper jar member 7 is designated by the reference numeral 17 in Figure 4 of the drawing.

It is believed that the many advantages of a drill jar in accordance with the present invention will be readily understood, and although the preferred embodiment of the invention is as illustrated and described, it is to be understood that changes in the details of construction and in the combination and arrangement of parts may be resorted to which will fall within the scope of the invention as claimed.

What is claimed is:—

- 20 A drill jar comprising a bit, a lower jar member threadedly connected with the upper end of the bit and including a threaded intermediate portion and further including a slotted upper portion, an upper jar member including a depending slotted portion slidably interlooped with the slotted portion of the lower jar member for operatively connecting said jar members together, the upper jar member further including a head and a threaded shank extending upwardly from the head, a socket member threadedly engaged with the shank and constituting means for connecting the drill cable to the upper jar member and having an elongated tapered upper portion, an elongated barrel enclosing the socket member and the jar members, said barrel having its lower end portion internally threaded and threadedly engaged with the threaded portion of the lower jar member, and an elongated reduced neck formed integrally with the upper end of the barrel through the cable passes, said neck being engageable by the tapered upper portion of said socket member for connecting the barrel to the cable should the socket member separate from the upper jar member or should the upper and lower jar members become separated.
- 50 In testimony whereof we affix our signatures.

JOHN N. KAUMANS.
ELISHA BRIDGES.
